United States Patent Office.

GEORGE I. WASHBURN, OF WORCESTER, MASSACHUSETTS.

Letters Patent No. 74,959, dated February 25, 1868.

IMPROVEMENT IN FEED-WATER HEATERS.

The Schedule referred to in these Letters Patent and making part of the same.

TO ALL WHOM IT MAY CONCERN:

Be it known that I, GEORGE I. WASHBURN, of Worcester, Worcester county, State of Massachusetts, have invented a new and useful Improvement in Feed-Water Apparatus; and I do hereby declare that the following is a full, clear, and exact description thereof, which will enable others skilled in the art to make and use the same, reference being had to the accompanying drawings, forming part of this specification.

The object of this invention is to utilize the exhaust steam of the engine which pumps water into the boiler; and the invention consists in condensing the exhaust steam by subjecting it to the cooling influence of the feed-water while the latter is on its way from the reservoir to the boiler. The heat of the exhaust steam is thus imparted to the feed-water, and contributes to effect the vaporization of the same, instead of being lost, as is the case in common steam-pumps.

Various methods of construction and arrangement may be employed, all of which embody the essential provisions which serve to attain the object contemplated under this improvement, namely, first, a steam-pump or pumps for forcing water into the boiler; and, second, a condensing-chamber or apartment, into or through which the exhaust steam of the pumping-engine is conveyed to be condensed by the water *in transitu* between the reservoir and pump or between the pump and the boiler.

The several figures of the accompanying drawings represent sectional elevations of different forms of apparatus embodying my invention, which will be described in the order of their numbers, like letters and figures indicating corresponding parts in the different views.

In Figure 1, two condensers, C D, are employed in connection with the pumping-engine, of which A is the steam-cylinder, and B the pump or water-cylinder; 1 is the steam-supply pipe, and 2 the exhaust-pipe of A; 3 is the pipe leading from the reservoir to the pump-cylinder, and 4 the pipe leading from B to the boiler. The condensers C and D may be enlarged portions of the respective pipes 3 and 4, but in the illustration the disjoined parts of each pipe are represented as leading into the upper and lower part of a distinct condensing-chamber. As the pump-piston B¹ is moved in the direction indicated by the black arrow, the consequent vacuum causes cold water to ascend from the reservoir into the condenser C, through the lower section of pipe 3, and hot water into the cylinder B, through the upper section of pipe 3, and during this movement the valve 5 opens and valve 6 closes. The vacuum produced by said stroke of the piston also causes the contents of the exhaust-pipe 2 to discharge into the condenser C. Said exhaust-pipe 2 traverses the condenser D in the form of a coil, and terminates within the condenser C in a similar coil, its extremity being guarded by a valve, 7, which opens to permit the pipe 2 to exhaust into the condenser, but closes to prevent the passage of the water from the chamber C into the pipe. A valve, e, in the lower end of the condenser C, (or a similar valve in the lower end of pipe 3,) prevents reflux of the elevated water, and keeps the condenser supplied with sufficient water for the purpose of condensation. When the motion of the piston B¹ is reversed, the valve 5 closes; the valve 6 opens, and the water is forced from pump-cylinder B to the boiler through the pipe 4 and condenser D. While D will be termed a surface-condenser, inasmuch as the exhaust steam passes through it without coming in contact with the water, C will be styled a-direct-contact condenser, both by reason of the discharge of the contents of the exhaust-pipe into the same and for the sake of distinction. The water in the surface-condenser, which maintains a sufficient constant bulk, may, under some conditions, be sufficient to effect the complete condensation of the exhaust steam; hence the surface-condenser may be the sole means for condensing the exhaust steam, in which case the water of condensation may be pumped or conveyed into the boiler by any suitable means. The same is true of the direct-contact condenser C, which, as employed alone, or without a separate surface-condenser, is shown in fig. 2. By prolonging the exhaust-pipe 2, under the arrangement shown in fig. 2, the condenser becomes a surface-condenser, located on the water-supply side of the pump-valves. This may be done when desirable.

In Figure 2 the steam-pump and its accessories and the condenser C are constructed and connected the same as in fig. 1, but the exit-water pipe 4 leads directly from the pump-cylinder B to the boiler instead of through a surface-condenser, as in fig. 1, and the exhaust-pipe 2 passes directly into the condenser C.

In Figure 3, the piston, within the steam-cylinder A, drives two plungers, B¹ B³, of the duplex pump B B², which is furnished with check-valves, as shown. The pump B² B³ raises the water from the reservoir through

the pipe 8, and forces it into the elevated condenser C through the pipe 9. This reservoir may be simply a tank, open or closed at top, and situated between the two sets of check-valves, or rather between the pump-cylinders. Water from this tank descends by gravity in the pipe 3 and floods the cylinder B, from which it is ejected into the boiler through the pipe 4.

In Figure 4, a single condenser, C, is employed in connection with two distinct steam-pumps. The two steam-cylinders A A exhaust into the condenser C through the respective pipes 2 2. The engine A B² B³ draws water from the reservoir through the pipe 8, and forces it into the condenser C through the pipe 9. The engine A B¹ takes water from the condenser through the pipe 3, and forces it into the boiler through the pipe 4.

In Figure 5 is shown a condenser, C, in connection with a double-acting force-pump, B B¹. In this case the engine exhausts into the condenser C, as before, but the pump first takes the water from the reservoir through an independent pipe, 8, then ejects it into the condenser through pipe 9, and then draws hot water from the condenser through pipe 3, and throws it into the boiler through pipe 4.

The various modifications of the invention which I have described above will naturally suggest many others, all involving the same general principles, and serving to effect a saving of heat, by utilizing the exhaust steam. The invention enables me to employ cheap solid pistons in the steam-cylinders of the pumps, inasmuch as any steam which may leak between the piston and cylinder is condensed and returned to the boiler without material inconvenience. A saving of power is due to the fact that the resistance opposed to the steam-piston of the pump is reduced by the vacuum which occurs when the pump draws from the condenser, such vacuum serving to promptly relieve the steam cylinder and exhaust-pipe of their contents. The check-valve 7 is especially conducive to the attainment of this result.

The direct uniform drawing and expelling action of the pump-pistons or plungers obviates failure in the operation of the pump, which failure might otherwise result from the deterioration or destruction of the vacuum by the vaporization of water or the pressure of air in the condenser or pipes. The direct drawing and forcing action of the pump will free the pipes and condenser of air or vapor, and a few strokes will suffice to start the pump into effective operation, notwithstanding a temporary drawback of this kind. The pipe 2 may be provided with a cock to shut off the exhaust steam from the condenser, and discharge the same elsewhere, when it becomes desirable to work the pump without condensing, so as to prevent the undue heating and vaporization of the water in the condenser, as in freeing a long pipe for the first time. This cock may be turned by hand, or it may be used in connection with a heat-expanding device or a float, which shall automatically regulate the passage of the exhaust steam to the condenser as desired. The single-acting pump-pistons may be made either solid, as herein represented, or they may be provided with valves for the passage of water, so as that water may be taken in at one end of the cylinder and discharged at the other.

I propose to use the double piston described in my patent, No. 48,802, dated September 5, 1865, and attach to each end of each of the two valve-pistons a single-acting plunger-piston, and of these four pistons two shall draw water and put it into condenser, and the other two take it from condenser and force it into the boiler. The condensers may be made in the same casting as the pump; a hollow base, for example.

Having thus described my invention, the following is what I claim as new, and desire to secure by Letters Patent:

1. The combination, with the condenser C, arranged between the reservoir and pump, of the surface-condenser D, fig. 1, situated between the pump and boiler, substantially as described.
2. The arrangement of the condenser between two pumps or two ends of the same pump, substantially as described.
3. A steam-pump and condensing-apparatus, constructed and arranged substantially as herein described.

To the above specification of my new and useful improvement in feed-water apparatus, I have signed my hand, this 13th day of August, A. D. 1867.

GEO. I. WASHBURN.
